Oct. 7, 2023 (CN) 202330645252.X

The ornamental design for a printer, as shown and described.

(51) **LOC (15) Cl.** **18-99**

DESCRIPTION

(52) **U.S. Cl.**

FIG. 1 is a front, left, and bottom perspective view of a printer, showing our design;

USPC **D18/19**

FIG. 2 is a front, right, and bottom perspective view thereof;

(58) **Field of Classification Search**

FIG. 3 is a rear, left, and bottom perspective view thereof;

USPC D18/14, 18, 19, 36-41, 45, 50, 53-56;

FIG. 4 is a rear, right, and bottom perspective view thereof;

D14/121, 301, 307

FIG. 5 is a front elevation view thereof;

CPC B41J 3/36; B41J 3/00; B41J 3/28; B41J

FIG. 6 is a rear elevation view thereof;

3/445; B41J 3/46; B41J 11/0045; B41J

FIG. 7 is a left side elevation view thereof;

2/3358; B41J 3/382; H04N 1/00204;

FIG. 8 is a right side elevation view thereof;

H04N

FIG. 9 is a top plan view thereof; and,

(Continued)

FIG. 10 is a bottom plan view thereof.

(56) **References Cited**

The broken lines that are immediately adjacent to the shaded areas, and contain additional broken line subject matter, depict the bounds of the claimed design, while all other broken lines are directed to portions of the printer that form no part of the claimed design.
